CIRCUIT BREAKERS

Donald H. Holdt, Cambridge, Md., assignor to Airpax Electronics Incorporated, Fort Lauderdale, Fla., a corporation of Maryland

Filed June 22, 1960, Ser. No. 37,942
16 Claims. (Cl. 200—106)

This invention relates to circuit breakers, more particularly to circuit breakers of the type provided with means for manually operating the circuit-controlling contacts between open and closed positions together with automatic tripping means for causing the contacts to move to open circuit position upon the occurrence of a predetermined amount of circuit current overload.

It is an object of the invention to provide an improved shockproof circuit breaker having a trip device that is simple, efficient, positive and reliable in operation.

A further object is to provide a circuit breaker that is light, compact, durable, safe and simple to use and sealed within a dustproof casing particularly adapted for use on vehicles, such as airplanes, trucks, etc.

A further object is to provide a circuit breaker wherein the manual control element for opening and closing the circuit-controlling contacts, when used as an ordinary switch, also functions to set the device for automatic operation under overload conditions.

A further object is to provide a circuit breaker employing a floating toggle linkage.

A further object is to provide a circuit breaker comprised largely of simple sheet metal stampings and readily available materials thereby rendering it easy and inexpensive to manufacture.

The invention itself, however, both as to structure and operation, together with the objects and advantages thereof, will best be understood from the following detailed description of a specific embodiment thereof when read in connection with the accompanying drawings, in which:

FIGURE 1 is in part a vertical sectional view taken on line I—I in FIGURE 3 but with the casing in section mounted on the device showing the circuit breaker mechanism in open position;

FIGURE 2 is a view like FIGURE 1 but with the circuit breaker mechanism in closed position;

FIGURE 3 is an end elevational view of the device viewed from the left in FIGURE 1 with the casing removed;

FIGURE 4 is an end elevational view of the device viewed from the right in FIGURE 2 with the casing removed;

FIGURE 5 is a fragmentary view in side elevation showing the positioning of the toggle linkage during movement of the circuit closing contacts when moved from open to closed position;

FIGURE 6 is a section taken on line VI—VI in FIGURE 1 showing the compound armature structure;

FIGURE 7 is a perspective view of the compound armature structure;

FIGURE 8 is a diagram of forces acting on the toggle linkage mechanism;

FIGURE 9 is a schematic showing of the electrical connections of the circuit breaker;

FIGURE 10 is a side elevational view of the main armature.

Referring to the drawings, the supporting frame comprises a support plate 1 and a side wall 2 depending therefrom, both formed from a single metal stamping. Fastened integrally as by welding to the side wall 2 at the bottom is a bifurcated terminal plate 3, each bifurcation of which carries a terminal 9 providing means to connect the structure to the circuit to be controlled. Each terminal

2

9 is insulated from the terminal plate 3 by means of glass insulation 10' or the like in a mounting bushing 10, as shown in FIGURE 1.

On the top of support plate 1 is rigidly mounted a toggle bushing 4 in which toggle handle or lever 6 is pivotally mounted intermediate its ends at 7 and extends down through support plate 1. A rubber diaphragm or seal 8 closes the opening around the handle 6 and as shown is bonded to both the handle 6 and bushing 4. The bushing 4 is shown threaded at 5 providing a mounting means for the circuit breaker structure.

As shown in FIGURES 1 and 2, a solenoid 11 suitably connected electrically to terminals 9 is mounted below plate 1 by means of depending members, or equivalent means 12 rigidly secured to the support plate 1. A compound armature structure A (FIGURE 7) is pivotally mounted, in operative relation to pole piece 13 of the solenoid, on shaft 14 supported at its ends by support side plate 2 and a laterally extending wing member 15 from the plate 2. As shown particularly in FIGURES 6 and 7, the compound armature A comprises in part an auxiliary armature 16 pivotally mounted on shaft 14 and having its upper end operably aligned with the solenoid pole piece 13. The auxiliary armature 16 in its lower part is bifurcated, the legs 17 and 18 thereof being of considerable length and of a size to balance the armature about shaft 14. Auxiliary armature 16 is limited in its counter-clockwise movement relative to the pole piece 13 (FIGURE 1) by means of a fixed stop 19 on a bracket 43 depending from a portion of back wall 2 (FIGURE 1). A whisker-type spring 20 is solder-anchored on plate wing extension 15 (FIGURE 1) and extends around the lower edge thereof and bears against the side of auxiliary armature 16 to constantly bias it anticlockwise whereby its leg 17 is normally held against stop 19 (FIGURES 1 and 2) when the solenoid is de-energized.

The main armature component 21 is also pivotally mounted on shaft 14 and in juxtaposition to the auxiliary armature 16. A spring 40 around shaft 14 urges it counterclockwise in FIGURES 1 and 7. This movement is limited by a side arm extension 21' on armature 21 engaging stop 42 on bracket 41 depending from frame wing 15. Stop abutments 19 and 42 are so adjusted that the upper end of main armature 21 is slightly angularly spaced relative to auxiliary armature 16 when the circuit and no overload condition obtains. The lower end of main armature 21 comprises a latch abutment 22 disposed medially of legs 17 and 18 for a purpose to be later described.

On a fixed pivot shaft 23 carried by the back wall 2 of the frame is mounted a relatively stiff but resiliently bendable lever 24 intermediate its length. At its end remote from the armature it is pivotally connected at 25 to a bifurcated toggle link 26 U-shaped at its upper end while at its free other end it carries a suitably insulated circuit closing contact 27. Immediately above lever 24 and pivotally mounted on the same fixed pivot shaft 23 is latch lever 28 of relatively rigid construction likewise carrying suitably insulated circuit closing contact 29 which is positioned so as to be engageable with contact 27 on lever 24. The end of latch lever 28 remote from the armature is bent to form a stop abutment finger 30 disposed between the bifurcations of toggle link 26 and engageable with a pin 31 carried by the bifurcations of link 26 at a point closely adjacent mounting shaft 25. The finger 30 and pin 31 when engaged limit the angular opening of latch lever 28 and arm 24 about their common pivot 23. The other free end of latch lever 28 is bent to form a latch member 32 adapted, under conditions to be explained, to engage the latching abutment 22 of main armature 21. A coiled spring 23' surrounds shaft 23 and has ends which bear respectively against

levers 24 and 28 to normally urge the circuit closing contacts 27 and 29 thereon apart into open circuit position.

The end of bifurcated toggle link 26, above and opposite its end pivoted at 25, is pivotally connected to the lower end of toggle handle 6 by means of a pivot pin 33. Also pivotally mounted on and carried by pin 33 and nested between the arms of the U-shaped portion of link 26 is a metallic spring guide and abutment member 34 which has an offset guide arm 34' extending therefrom and slidably engaging in a guide and aligning aperture 36 in a non-metallic spring guiding and mounting member 35 pivotally mounted at 37 at a fixed point on frame wall 2. Mounted between and carried by members 34 and 35 is a toggle actuating compression spring 38 which constantly tends to bias member 34, as well as the ends of members 6 and 26 also pivotally attached to pin 33, away from member 35 and its fixed pivot shaft 37. The guide member 34' maintains the spring support members 34 and 35 in proper alignment at all times. To limit the distance that spring support member 34 may move under the action of spring 38 an abutment 39 is provided on frame wing 15 in alignment with the path of movement of spring support 34, the latter having a suitable abutment surface for engagement with abutment 39.

A suitable thin metallic casing 45, of rectangular shape, in the particular embodiment illustrated, compactly encloses the circuit breaker mechanism mounted below support plate 1 and is apertured at its bottom to snugly fit in sealing relation around the terminal bushings 10. The upper edge or opening of the casing closely engages the periphery of support plate 1 and is sweat-soldered thereto in sealing relation. The casing 45, together with the seal 8 around the toggle handle 6, thus seals the circuit breaker mechanism against the admission of dust and moisture and their harmful influences.

The combined circuit breaker and switch operates as follows:

With the parts in the position in FIGURE 1, and the contacts 27, 29 in open position, the toggle handle 6 is manually swung counter-clockwise to the position shown in FIGURE 2. During such movement pivot pin 33, and the spring abutment 34 and upper end of toggle link 26 pivotally connected thereto, are moved to the right compressing toggle spring 38. As link 26, which is actually floating, in view of its mounting at both ends on movable pivots, is thus moved, its lower end, through its pivotal attachment with lever 24 at 25, is forced downwardly. The initial downward movement causes clockwise movement of lever 24 about its fixed pivot 23, causing spring 23' to yieldingly urge latch lever 28 clockwise about its common pivot 23 such that its latch end 32 engages the latch member 22 of the main armature 16 which is in its path, as indicated in FIGURES 2 and 5.

Further downward movement of link 26 causes further clockwise pivotal movement of lever 24 bringing contact 27 up into engagement with contact 29 on latch lever 28 and, at the same time, further increasing the biasing action of spring 23'. At this point of actuation contacts 27, 29 are closed and substantially no flexure obtains in lever 24. The end of lever 24 lies at the point 24" with lever 24 positioned as shown in dotted lines in FIGURE 5. Throughout the movement of parts thus far described in the operation of the device toggle pivot 33 lies to the left of a straight line extending between handle pivot 7 and toggle pivot 25. Since latch lever 28 cannot move upward any further, due to its latch end 32 abutting latch abutment 22 of the main armature 21 due to the upward pressure of contact 27 on contact 29 and it being mounted near its other end on fixed pivot 23, continued movement of handle 6 toward the FIGURE 2 position forces toggle link 26 further downward. This downward movement pushes pivot pin 25 further downward causing a downward flexure and deflection of the right hand end 24' of lever 24 lying between pivots 23 and 25 while a slight

upward bowing occurs in the lever between its pivot 23 and contact 29. The downward deflection of the end 24' of lever 24 is at a maximum when toggle pivot pin 33 is at dead center, that is, lies in the straight line passing through pivots 7 and 25, as indicated at 33' in FIGURE 5. The final movement of handle 6 to the FIGURE 2 position swings toggle pivot pin 33 past dead center to the cocked position indicated at 33" in FIGURE 5. As this occurs the deflected end of the lever flexes upwardly by the force thus stored in it to substantially the straight line position shown in FIGURE 2 thereby exerting sufficient force, by its inherent resistance to flexure, against the end of the floating toggle linkage formed by the lower end of handle 6 and toggle link 26, to hold it in its cocked (over dead center) position. It will be noted that while spring 38 is highly compressed at this time, its force acting on toggle link 26 is of a very small value by reason of the fact, as clearly apparent in FIGURES 2 and 5, that the greater component of its force is directed up through handle pivot 7, the toggle link pivot 33 being disposed just slightly out of and to the left of a straight line passing through handle pivot 7 and fixed spring abutment pivot 37. Thus the contacts 27, 29 are held in engagement by the floating toggle just described so long as the latch end 22 of the main armature 16 is held in engagement with end 32 of latch lever 28.

Assuming the circuit breaker device is connected at its terminals 9, 9 into a circuit it is adapted to control, if the current only slightly exceeds a 100 percent load, the electromagnetic force in solenoid 11 will only exert sufficient force on auxiliary armature 16 to move it clockwise (FIGURE 1) into contact with the upper end of main armature 21 without releasing the latch abutment 22 out of the path of latch member 32 on the adjacent end of latch lever 28.

However, in the event of a predetermined overload (125 percent in the embodiment illustrated) the solenoid 11 will cause a small further clockwise movement of the auxiliary armature 16 which then thrusts against the upper portion of the main armature 21. This slight movement of armature 21 oscillates its latch abutment 22 clockwise out of engagement with latch finger 32 on latch lever 28. Coil springs 23' then immediately acts to spread latch lever 28 and arm 24 apart about their fixed pivot shaft 23, releasing toggle abutment means 24', 25, thereby permitting the small but effective component of force of toggle spring 38 to move pin 33 to the left (FIGURE 2). Immediately the full force of toggle spring 38 becomes effective to thrust and yieldingly hold the toggle handle 6 and toggle link 26 to the fully released position shown in FIGURE 1 until the mechanism is again manually operated as above-described to again close contacts 27, 29.

The circuit breaker may obviously be used as a conventional manually operable switch. When it is so used the circuit is closed at 27, 29 in exactly the same way as previously described by oscillating handle 6 from the position in FIGURE 1 to that shown in FIGURE 2 when used as a circuit breaker. All components will then be disposed as illustrated in FIGURE 2.

To manually open the circuit at 27, 29 the handle 6 is returned from its FIGURE 2 position to its FIGURE 1 position. From the previous description it is apparent that with latch lever 28 and arm 24 both being initially latched and held in the position shown in FIGURE 2 the manual oscillation of handle 6 to the FIGURE 1 position swings toggle pin 33 to the left in FIGURE 1 forcing the toggle link downwardly to depress or deflect the right-hand end 24' of arm 24 while toggle pin 33 passes through dead center, as happened when the contacts were manually closed, as previously described relative to circuit breaker use. The toggle spring 38 then obviously assists in the movement of the handle to the fully open contact position. It is thus obvious that the circuit can be manually opened or closed through the device at 27, 29 regard-

less of the degree of excitation of solenoid 11 or even when no current flows therethrough.

While the invention has been shown and described in accordance with the patent statutes, it is to be understood that various changes in the details of the structure may be made without departing from the spirit of the invention. It is desired therefore that the invention be limited only by the scope of the appended claims.

What is claimed is:

1. In an automatic overload circuit breaker comprising in combination, a supporting frame having mounted thereon a manual actuating member, dual lever means pivotally mounted intermediate their ends at a point on said supporting frame spaced from said actuating member, circuit-controlling contact means carried solely on said dual lever means, an electromagnetic device electrically interconnected with said contact means and including armature means, linkage means pivotally connecting one end of one of said dual lever means and said manual actuating member and forming therewith a floating toggle linkage, the other of said dual lever means comprising a latch means for said floating toggle linkage and having thereon a latch device operably associated with latch means on said armature means, an actuating spring means operably connected with said floating toggle linkage intermediate its ends and so mounted as to move said toggle linkage when unlatched to cause opening of said circuit closing means when the electromagnetic means under predetermined overload conditions actuates said armature means to release the said latch device on said other dual lever.

2. An automatic overload circuit breaker comprising in combination a supporting frame, a manually actuated lever pivoted intermediate its ends on said frame, a second lever, means pivoting said second lever intermediate its ends on said frame at a point spaced from said first mentioned lever, link means pivotally connecting one end of each of said first and second levers thereby forming a floating toggle linkage, spring means effecting movement of said toggle linkage, a third lever forming a latch means pivotally mounting said second lever, one end of said third lever forming a latch means, circuit closing contact means mounted on said pivoted second and third levers, a solenoid and pivoted armature means therefor mounted on said frame, said armature having a latch element thereon operable to be engaged by the said latch element on said third lever, said third lever and armature latch elements operable together to hold the floating toggle linkage stationary against the action of the spring means when manually moved in one direction over dead center, the solenoid being responsive to circuit overload conditions to release the floating toggle linkage whereby the spring means moves the toggle linkage and circuit contacts to open position.

3. In a device of the character described, a support structure, manual actuating lever means pivoted intermediate its length thereon, fixed pivot means on said support structure and spaced from said actuating lever means, two lever means mounted on said fixed pivot means and disposed substantially normal to said manual actuating lever means, spring means acting between said two lever means tending to move said lever means angularly apart, a bifurcated link pivotally connected at its ends to one end each of the manual actuating lever and one of said two lever means thereby forming a floating toggle linkage, the second of said two lever means having an end lying between the bifurcations of said link, pin means on said link coacting with said lever end to limit its arcuate movement in one direction, a latch finger on the other end of said second other lever means, a circuit closing and opening contact mounted on said second other lever intermediate its end latch finger and pivotal mounting, a coacting circuit contact mounted on the free end of said one of the two lever means, a pivoted

latch means on said support structure, said latch being operable to engage the latch finger on the end of said second other lever, spring means urging said latch into the path of said latch finger, spring means positioned to constantly exert an actuating force through the pivotal connection of said link and manually operating member, said latch and said two levers in cooperation with the circuit contacts carried thereby when engaged holding the floating toggle linkage over dead center against the action of said toggle spring means, the manual actuating member being operable to move the floating toggle linkage against the holding action of the latch and two lever means to a position back over dead center whereby the full force of the toggle spring is effective to complete the contact opening movement.

4. In a device as claimed in claim 3 including electromagnetic means and an armature therefor, said armature comprising said pivoted latch means.

5. The device as defined in claim 3 including motor means, said pivoted latch means comprising a part of said motor means.

6. A circuit breaker comprising a mounting frame, a manually operable first lever pivoted intermediate its length on said frame, a second lever pivotally mounted intermediate its length on said frame in spaced relation to said manually operable lever, a link pivotally connected by means of pin means to an end of said second lever, said first lever and said second lever and link forming a floating toggle linkage, the said second lever being operably associated with releasable latching means whereby said second lever may be held in a fixed position, toggle actuating spring means mounted on the frame to thrust against said toggle linkage, said spring means moving said floating toggle linkage through a dead center position when the latching means operably associated with the said second lever is released.

7. The circuit breaker defined in claim 6 wherein circuit controlling contact means are carried by said second lever means and said releasable latch lever means, motor means mounted on said frame, said motor means being electrically connected to said contacts and operable under overload conditions in an electric circuit controlled thereby to release said latching means and cause said toggle spring through said floating toggle linkage to open said electric circuit.

8. The device as recited in claim 6 wherein the pin means connecting said manually operable first lever and said link pivotally carries a first spring abutment member, a second spring abutment member pivotally mounted on said frame, an offset guide arm on said first spring abutment member engaging an aperture in said second spring abutment member to maintain said abutment members in alignment with each other, the toggle actuating spring being mounted on said abutment members.

9. The device as recited in claim 8 wherein the said link is U-shaped at its end adjacent its pivotal connection to said manually operable lever means, said spring abutment means carried by said toggle pin means pivotally connecting said manual lever and said link being disposed between the arms of said U-shaped end of said link.

10. The structure as defined in claim 6 wherein circuit controlling contact means are carried by said second lever means and said latching means, electromagnetic means mounted on said frame being electrically connected to said contacts and operable under overload conditions in a circuit controlled thereby to release said latching means and cause said toggle spring through said floating toggle to open said circuit.

11. The structure as defined in claim 10 wherein said latching means comprises a rigid lever pivotally mounted on the means pivotally mounting said second lever, and spring means interposed between said rigid lever and said second lever means, said last-named spring means releasing said toggle means for actuation by said toggle

spring when said rigid lever is released by said electro-magnetic means.

12. The structure as defined in claim 11 wherein an end of said rigid lever forms a limit stop means in association with pin means on said link operative to limit opening movement of said rigid lever under the action of said last-named spring means.

13. The device as defined in claim 12 including abutment means on said frame structure engageable by spring abutment means on said toggle linkage to limit its movement in one direction under the action of said toggle spring.

14. In a circuit breaker having relatively movably mounted lever means carrying co-acting contact means for opening and closing an electric circuit, manual means to actuate said relatively movably mounted contact means, latch means to hold said contact means closed, motor means in said electric circuit effective to release said latch means on occurrence of predetermined circuit overload, the combination therewith of a floating toggle linkage connecting said manually actuatable means and one of said movably mounted contact means, spring means acting through the point of connection of said floating toggle linkage with said manual means to cause said floating toggle linkage to open said movably mounted contact means when said latch means is released by said motor means.

15. A circuit breaker comprising a frame means, a manually operable first lever pivoted intermediate its length on said frame means, means pivotally mounting a slightly resilient second lever intermediate its length on said frame means in spaced relation to said manually operable lever, electrical contact means mounted at one end on said second lever, a link, means pivotally connecting said link to the opposite end of said second lever and the adjacent end of said first lever, said first lever and said second lever and link forming a floating toggle linkage, a rigid latch lever pivoted intermediate its length

on said pivotal means in overlying relation to said second lever and with one of its ends lying adjacent said link, electrical contact means mounted intermediate the length of said latch lever in cooperative relation to said first mentioned electrical contact means, spring means biasing said second lever and latch lever toward contact open position, abutment means movable to engage the opposite end of said latch lever, said second lever, when acted upon by said first lever means in opposition to said spring means to engage said contacts while said movable abutment means is engaged with said opposite end of said latch lever, being deflected out of alignment at its said opposite end as the toggle linkage passes through its dead center position by the operation of said first lever to hold said contacts in engagement with each other.

16. The circuit breaker as defined in claim 15 further including spring means mounted to exert a force on said toggle linkage connection of said first lever with said link tending to open said contacts when held closed by the said deflection of said second lever, motor means connected in an electrical circuit including said electrical contact means, said motor means operable on a predetermined overload to actuate said movable abutment means out of engagement with said opposite end of said latch lever to thereby release said toggle linkage and cause movement of said contact means to open position by said toggle spring means.
